R. E. JAMES

AUTOMATIC WATER INJECTOR FOR STEAM ENGINE BOILERS

Filed May 27, 1924

UNITED STATES PATENT OFFICE.

ROBERT E. JAMES, OF DURANT, OKLAHOMA.

AUTOMATIC WATER INJECTOR FOR STEAM-ENGINE BOILERS.

Application filed May 27, 1924. Serial No. 716,242.

To all whom it may concern:

Be it known that I, ROBERT E. JAMES, a citizen of the United States, residing at Durant, in the county of Bryan and State of Oklahoma, have invented certain new and useful Improvements in Automatic Water Injectors for Steam-Engine Boilers, of which the following is a specification, reference being had to the accompanying drawings.

This invention relates to injectors for steam engine boilers, and the object of the invention is to provide automatically acting means for keeping the boiler filled with water to a predetermined point above the lower gauge cocks thereof or at any desired height below the uppermost gauge cock, the mechanism comprising means whereby steam may be taken from the boiler just above the water line of the uppermost gauge cock and sent through an injector to thereby draw water upward from the water supply and force the water into the boiler, the construction being such that when the water rises above its predetermined water line it will cut off passage of steam through the injector and thus the flow of water will stop, and when the water falls below this predetermined water line the injector will immediately commence to act to force water into the boiler.

A further object is to provide a construction of this character which is very simple, which may be easily put in place without altering the character of the boiler at all, and which permits the boiler to be readily altered to conform to the invention.

Other objects will appear in the course of the following description.

My invention is illustrated in the accompanying drawing, wherein:

Figure 1 is a side elevation of a boiler of any ordinary type having my automatic water feeding mechanism applied thereto;

Figure 2 is an enlarged elevation of the feeding device and a portion of the boiler.

Referring to the drawing, 10 designates a boiler, such as a stationary boiler, though the invention is adapted to be applied to any boiler, and 11 the steam dome. 12 designates the fire box and 13 the front boiler sheet. Entering the front boiler sheet are a vertical series of gauge cocks of any usual and suitable construction and designated 14, 15 and 16. These are ordinarily found on engines of this character to de-

termine the level of the water in the boiler and these gauge cocks enable the operator to keep either one, two or three "gauges" of water as desired, but the operator must 60 keep a close watch on the gauges in order to do so.

Disposed in connection with the boiler is an injector 17 of any ordinary or usual type having the supply pipe 18 and the pipe 19 which extends into the boiler and through which the water is forced. This injector ordinarily is connected to the steam dome by a pipe extending upward from the injector and entering the top of the steam dome. 70 This pipe is designated 20 and is provided with a valve 21.

So far I have described the ordinary construction of steam boiler with the injector therefor, but in order to reconstruct the 75 boiler in accordance with my invention and place my automatic gauge in position it is necessary to remove the ordinary gauge as, for instance, the gauge 16 and place thereon a nipple and a T 22. The gauge 16 is 80 then placed back into the T and a pipe 24 is connected to the T and leads back to the injector through a T 25. The T 22 is provided with a valve 26, and in order to use the injector as now arranged it is necessary to close the valve 21 in the steam line 85 20 and open valve 26.

In order to fill the boiler for over night in case the boiler is not being operated at night and in which case the boiler is to be 90 filled almost full of water and before firing up, then the valve 26 is closed and the valve 21 opened and the steam from the steam dome will act through the injector in the ordinary manner to draw water from the 95 pipe 18 and force the water through the pipe 19 into the boiler, but in case it is desired merely to fill the boiler to a height equal to the uppermost gauge, then the valve 21 is closed and the valve 26 is opened. So long 100

as the water line is below a predetermined point, that is below the gauge 16, the steam from the boiler will pass through the gauge and out through the pipe 24 into the injector and thus cause the water from the pipe 18 to be discharged into the boiler, but when the water has risen to such a point that it prevents the passage of steam from the interior of the boiler into the gauge 16, then the feeding of steam to the injector is cut off because the water is above the steam intake and the injector stops in its opera- 110

tion. When the water has lowered, however, below the gauge cock 16, the steam intake will be automatically opened and steam will pass into the injector and start it working again and thus the water in the boiler will be kept at a constant height.

Where this device is used it is not necessary to keep a man at the boiler when firing in oil. The fire is regulated to a certain height and the injector is turned on. After that it is perfectly safe to leave the boiler alone, as there will never be any lack of water in the boiler because of the automatic operation of this construction.

It will be seen that with this device the boiler does not have to be filled entirely full and kept entirely full, but that it may be kept at a predetermined height equal to that particular gauge cock to which the pipe 24 is connected. Thus if the connection is made at the topmost gauge, the boiler will carry three gauges of water, if at the second gauge it will carry two gauges of water, and, of course, if the member 24 communicates with the lowermost gauge cock the water will remain at this level at all times and be automatically controlled. This device is made to fit on any style of boiler but is particularly adapted for boilers used in the oil fields and which are fired by means of oil. It will be obvious, however, that the device may work on any form of boiler as, for instance, on a railroad locomotive boiler, though it is particularly intended for use on all kinds of stationary boilers. By retaining the pipe 20 and its connection to the top of the steam dome, it is obvious that the boiler may be entirely filled with water whenever desired by the use of the injecting valves but that, on the other hand, the boiler may be kept filled to the uppermost gauge automatically and without requiring any attention.

I do not wish to be limited to the details of construction, as it is obvious that these might be varied in many ways without departing from the spirit of the invention.

I claim:

1. In a steam boiler of the character described, the combination with an injector for supplying the boiler with feed water, of a series of gauge cocks extending through the front of the boiler and disposed in vertical series, and a steam supply pipe for said injector having its inlet end engaged with one of said gauge cocks.

2. In a steam boiler having a steam dome, the combination with an injector for supplying the boiler with feed water, of a steam supply pipe for said injector having its inlet opening into the steam dome, a manually operable valve in the supply pipe, a second steam supply pipe, a manually operable valve in said supply pipe, and a gauge cock extending through the front of the boiler and to which the steam supply pipe is connected whereby to cause the admission of steam through said gauge cock to the injector when the level of the water has lowered below the gauge cock and the stoppage of the steam flow to the injector when the level of the water has risen above the gauge cock.

3. In a boiler having a steam dome and having a vertical series of gauge cocks extending to the front of the boiler, an injector, means for supplying water to the injector including a pipe extending upward from the injector and into the steam dome, said pipe being provided with a manually operable valve, a T connected to one of the gauge cocks, and a pipe connection extending from said T to the injector and provided with a valve whereby to permit the first named supply pipe to be cut off and the second named pipe opened to thereby automatically hold the water pipe level with the gauge cock and automatically operate the injector when the water falls below the level of the gauge cock.

In testimony whereof I hereunto affix my signature.

ROBERT E. JAMES.
